UNITED STATES PATENT OFFICE

140,271

DESIGN FOR AN OPTICAL FRAME

Robert Weber, New York, N. Y.

Application June 10, 1944, Serial No. 113,954

Term of patent 7 years

(Cl. D57—1)

To all whom it may concern:

Be it known that I, Robert Weber, a citizen of the United States and a resident of the city of New York, in the county of New York and State of New York, have invented a new, original, and ornamental Design for an Optical Frame, of which the following is a specification, reference being had to the accompanying drawing, forming a part thereof.

Fig. 1 is a front view of an optical frame showing my design.

Fig. 2 is a top view thereof.

Fig. 3 is a side view of the optical frame shown in Figs. 1 and 2.

The characteristic features of my design reside in the specific shape of the form, in combination with a bridge with corners at an angle to the eyepiece, all as shown.

I claim:

The ornamental design for an optical frame, substantially as shown and described.

ROBERT WEBER.
